CLAIM

USPC ..... D8/394—395, 71—74, 499, 354, 355, 373,

The ornamental design for a cross wire connecting device,
as shown and described.

D8/356, 383; D19/65

DESCRIPTION

CPC . D06F 55/00; A41B 3/08; A41F 15/02; F16B

FIG. 1 is a perspective view of the cross wire connecting
device;

19/1081; G09F 3/14; B42F 1/006; B42F

FIG. 2 is a left side view of the cross wire connecting device;

1/08; B42F 9/001; A47F 7/02

FIG. 3 is a right side view of the cross wire connecting device;

See application file for complete search history.

FIG. 4 is a top view of the cross wire connecting device;

FIG. 5 is a bottom view of the cross wire connecting device;

FIG. 6 is a front view of the cross wire connecting device;
and,

FIG. 7 is a back view of the cross wire connecting device.

FIG. 1 Claim, 6 Drawing Sheets
